UNITED STATES PATENT OFFICE.

CHARLES W. MEASON, OF WALNUT, KANSAS, ASSIGNOR OF ONE-HALF TO
JAMES M. GOFF, OF SAME PLACE.

NUT-LOCK.

SPECIFICATION forming part of Letters Patent No. 273,871, dated March 13, 1883.

Application filed January 18, 1883. (No model.)

To all whom it may concern:

Be it known that I, CHARLES W. MEASON, a citizen of the United States, residing at Walnut, in the county of Crawford and State of 5 Kansas, have invented a new and useful Nut-Lock, of which the following is a specification, reference being had to the accompanying drawings.

This invention relates to nut-locks for rail-
road fish-joints and for other purposes where
it is desirable or necessary to secure nuts
against working loose by the shaking of the
parts to which they are attached; and it has
for its object to provide a simple and convenient
device, which may be readily applied or de-
tached, as will be hereinafter fully described,
and particularly pointed out in the claim.

In the drawings hereto annexed, Figure 1
is a perspective view, showing my improved
nut-lock applied to a railroad fish-joint. Fig.
2 is a horizontal sectional view of the same.

The same letters refer to the same parts in
both figures.

A in the drawings designates the rail, B
the fish-plate, C the bolt, and D the nut, all of
which are of the usual well-known construc-
tion.

E is a flat spring, which is bent so as to form
two leaves, F G, the lower one of which, F,
which is the shortest, is provided near its
end with a perforation, H, to receive the bolt,
upon which the said spring is adjusted in such

a manner that its upper leaf, G, shall extend
over the said bolt and terminate between the
nuts of two adjoining bolts. Between the said
nuts, which are screwed down tightly, is placed
a block, K, the ends of which may be either
square or beveled, so as to abut against the
sides or edges of the nuts, which are thereby
prevented from turning. The face of the 35
block K has a longitudinal groove or recess,
L, to receive the end of the upper leaf of the
spring E, which serves to hold the said block
securely in position, the spring itself being
held by the nut upon the bolt upon which it 45
is adjusted. When desired, by simply releas-
ing the pressure of the spring, the block K
may be easily removed for the purpose of per-
mitting the nuts to be unscrewed.

I claim as my invention and desire to secure 50
by Letters Patent of the United States—

In a nut-lock, the combination, with a flat
spring bent so as to form two leaves of unequal
length, the lower short one of which is provid-
ed with a bolt-hole, of a block having a longi-
tudinal groove or recess to receive the end of 55
the upper spring, substantially as set forth.

In testimony that I claim the foregoing as
my own I have hereto affixed my signature in
presence of two witnesses.

CHARLES WILLIAM MEASON.
